UNITED STATES PATENT OFFICE.

GEORGE WILSON GOSS, OF WICHITA FALLS, TEXAS.

COMBINATION TUBING DRAINER AND PULLER.

Application filed August 8, 1925. Serial No. 48,969.

To all whom it may concern:

Be it known that I, GEORGE WILSON Goss, a citizen of the United States, residing at Wichita Falls, in the county of Wichita and State of Texas, have invented certain new and useful Improvements in Combination Tubing Drainers and Pullers, of which the following is a specification.

This invention relates to well pumping equipment and it has particular reference to a certain improvement in standing valve structures, the primary object of which is to provide an efficient means whereby that element may be automatically opened while within the well tubing by the actuation of the traveling valve thereabove, to permit the said tubing to be drained of its contents preparatory to pulling, thus to obviate possible loss accruing from waste of fluid resultant from such pulling.

The invention also contemplates in its provisions, a locking means within the standing valve, whereby to hold its valve in open position, should it be required to also withdraw the standing valve, as a further expedient in the saving of time.

Further, the invention aims in its objects to arrange said valve opening means in such a manner as to unseat the valve on the upward stroke of the traveling valve, to thus overcome the excessive weight of the fluid bearing on the valve.

Still further, certain other modifications are provided in the invention, when required to use either the tubing drainer or the valve puller alone.

With the foregoing and other objects and advantages in view, the invention has particular reference to certain novel features of construction and assembly of parts, by which these objects are attained, which will be set forth and manifested in the course of the following detail description and illustrated in the accompanying drawings, wherein:

Figure 1 represents a view in vertical elevation, appearing partly in section.

Figure 2 is also a view in vertical elevation of the standing valve in axial cross-section, showing the draining mechanism therein.

Figure 3 represents a vertical elevational view of the invention extended.

Figure 4 is a modified form of the invention in vertical elevation, from which the valve pulling arrangement has been deleted, showing the valve in open position.

Figure 5 is a fragmentary sectional view of the structure illustrated in Figure 4, showing the valve seated.

Figure 6 is a detail view of the rotating 60 plug, which is adapted to be threaded into the lower end of the traveling valve.

Figure 7 is a further modified form of the invention, in which the elements thereof are limited to a valve pulling device, and 65

Figure 8 is a further view of Figure 7 in vertical elevation, showing the pulling collar in place thereon.

In proceeding in accordance with the foregoing, 1 denotes the standing valve body, 70 which is positioned at a point adjacent the bottom of the well tubing, not shown. The valve body does not depart from the usual construction in such cases, but is provided with a plurality of superimposed leather 75 packing rings 2, circumferentially surrounding the lower portion 3 of the body 1.

Within the cage 4, the usual ball valve 5 is disposed upon the seat 6 provided by the lower portion 3 therefor. The body of the 80 valve is diminished at 6^a, directly above the cage 4, providing a shoulder 7, whereon is seated a compression spring 8. Reciprocable freely within the diminished portion 6^a, is a plunger head 9, clearly illustrated in 85 Figure 2, and to the bottom of which is securely affixed a spring leaf or tongue 10, having a protruding finger 11 thereon, which constitutes the locking means for the valve openings means, hereinafter more 90 clearly described. A pair of lateral pins 12 are provided upon the head 9, and are arranged to actuate within the L shaped slots 13 in the portion 6^a of the valve, whereby to engage the top of the spring 8 thereby to 95 compress the same.

The tubular collar 14, surrounding the diminished portion 6^a of the valve, is provided with oppositely disposed inverted L shaped slots 15, which slots are arranged to 100 be received by pins 16, situated upon the diminished portion 6^a of the valve. It is understood that this collar 14 is screwed upon the lower end of the traveling valve and is actuated thereby.

The traveling valve, with which the present invention operates, has not been illustrated in the drawings as its construction is well known, however, the latter is arranged to be simultaneously drained with 110 the draining of the standing valve, which function is performed by the rod 17^a,

threaded into the plunger head 9 and extending upwardly into the traveling valve, whereby to engage with and dislodge its valve upon downward stroke of the said traveling valve. This action causes release of the liquid suspended by the traveling valve, as well as that retained above the standing valve.

The valve locking means, as mentioned in the foregoing, constitutes in addition to the finger 11, a slot 18 in one side of one of the apertures forming the cage 4, and upon pressure of the head 9, imposed by the downward action of the traveling valve, the finger 11 assumes a position at a level with the slot 18, and rotation imparted to the traveling valve through the sucker rod upon which the same is mounted, causes the finger 11 to enter the slot 18, to thereby hold the head 9 from upward movement. The valve may be held in this position during the pulling of the tubing or may be reversely rotated to release the valve, should it be desired to only drain the tubing and valves to dispense with sand settling and other extraneous matter accumulated therein.

It being assumed in general practice, that the standing valve occupies a position adjacent the bottom of the well, while the collar 14, shown in engagement with the diminished portion 6^a of the valve body 1, is rigidly screwed upon the bottom of the traveling valve (not shown). When it is required to drain the tubing preparatory to pulling, the traveling valve is lowered to effect an engagement as shown, whereby to align the slots 15 of the collar 14 with the pins 16 disposed upon the portion 6^a. Further downward pressure causes compression of the spring 8, due to its engagement by the pins 12 of the head 9, upon which the collar 14 rests. When the head 9 reaches its lowest point, the tongue 10 assumes a position between the ball valve 5 and the wall of the cage 4, preparatory to raising the ball 5 upon upward movement of the traveling valve.

It is well known that the weight of the volume of oil contained within the entire tubing is excessive, and in several instances, attempts have been made to unseat the valve by mechanism actuated by the downward action of the traveling valve, but due to the enormous weight of the fluid, these attempts have thus far proved unsuccessful. Therefore, the present invention provides for a slight expansion of the spring 8, after engagement of the collar 14 with the standing valve, to cause depression of the head 9, such expansion being permitted by an offset portion α in the lateral portion of the inverted L shaped slots 15. When engagement of the latter with the pins 16 is accomplished to place the tongue 10 in the position as previously set forth, the collar 14 is rotated to per-

mit the pins 16 to be received by the offset α , thus affording a slight expansion of the spring 8, sufficient to raise the ball 5 a suitable distance upwardly to allow passage of the fluid thereby. In this manner, a greater lift may be accomplished to overcome the weight of the fluid against the ball.

The two modifications and their associated elements, illustrated in Figures 4 to 8 inclusive, may be employed when required to alternately pull or drain the tubing. The structure illustrated in Figure 4 is provided with the usual cage having a tubular neck 17 thereon, through which a plunger 18^b reciprocates, which latter is provided with a slotted head 18^a, as shown. This plunger is controlled in its movement by a compression spring 19, disposed interiorly of the neck. The function of this structure is similar to that shown in Figure 1, however, the pulling arrangement constituting the collar 14 is obviated. Such arrangement is replaced by the slotted head 18^a, arranged to receive the rotating plug 20, shown in detail in Figure 6, which is mounted upon the lower end of the traveling valve and is rotated to in turn rotate the plunger 18 whereby to lock the tongue 10 in the position illustrated in Figure 4.

In Figure 7 is shown a device in which the tubing drainer arrangement is obviated. This device consists of the usual standing valve provided with a neck 21, having extending therethrough, a horizontal pin 22, below which is retained a compression spring 23. The collar 24, similar to the collar 14, shown in Figures 1, 2 and 3, is also mounted upon the lower end of the traveling valve, not shown, and the slots 25 therein are aligned to receive the pins 22 on the neck 21, whereupon the sucker rod is rotated to lock the collar 24 in the position shown in Figure 8, whereby to withdraw the valve.

The invention has been described as including all the elements set forth in the appended claims, however it should be herein understood that certain minor changes and modifications may be made in the invention without departing from the spirit and intent thereof, or the subject matter of said claims.

I claim:

1. In a standing valve, having a ball valve therein, including in combination with the traveling valve; a slotted collar mounted beneath said traveling valve; a plunger reciprocable within said standing valve; a tongue depending from said plunger; means on said standing valve to receive said slotted collar upon downward movement of said traveling valve to effect contact of said tongue with said ball valve; means to effect limited upward movement of said plunger and tongue to unseat the said valve, and means to lock said plunger in said latter position.

2. In a standing valve, a draining means therefor including in combination with the traveling valve, a spring controlled member reciprocable within said standing valve provided with a depending tongue; a collar mounted below said traveling valve to be received by said reciprocating member, and means to cause depression of said reciprocating member by contact therewith by said 10 collar to effect engagement of said tongue with the valve preparatory to unseating the latter, and means to permit slight expansion of said spring whereby to raise said valve from its seat.
- 15 3. In a standing valve structure, a tubing draining means therefor in combination with a traveling valve; a spring controlled rod and plunger reciprocably mounted within said standing valve having means depending therefrom to engage its valve; a collar threaded to said traveling valve arranged to actuate said rod and plunger downwardly upon contact therewith; means to permit limited expansion of said spring 20 to raise said plunger and rod to simultaneously unseat the valves in the standing valve and traveling valve, and means to lock the valves in the latter position.
- 25 4. A standing valve having a plunger reciprocably mounted therein provided with a depending tongue arranged to engage behind its valve when actuated, to its lowest position preparatory to unseating the latter; means to effect such actuation, and means to permit limited upward movement of said plunger and tongue to raise the valve from its seat.
- 30 5. A standing valve structure including a tubing draining means comprising a plunger reciprocably mounted in said standing valve provided with a valve engaging member; means to cause engagement of said member with the valve; means to permit slight upward movement of said 35 member to unseat the valve, and means to lock said valve in open position.
6. In a tubing drainer, the combination with a traveling valve of a standing valve provided with a neck having a spring controlled plunger therein; said plunger provided with a downwardly depending valve engaging member; a locking means for said valve engaging member; a slotted head on said plunger; means on said traveling valve to engage said slotted head to cause depression of said plunger, said depression to effect engagement of said valve engaging member with the valve preparatory to unseating; means to rotate said plunger to lock said valve engaging member, and means to cause unseating action of said valve upon release of said locking means.
7. In a standing valve, a tubing draining means therefor, including in combination with the traveling valve, an interior valve and valve opening mechanism; said mechanism comprising a plunger having a yieldable tongue depending therefrom, whereby upon contact of said traveling valve against the plunger, said tongue will engage behind said interior valve preparatory to lifting the latter, and means to cause limited upward movement of said tongue to move the valve from its seat.
8. A standing valve having a movable plunger therein; an interior valve in the said standing valve arranged to maintain normal closed position of the latter; yieldable means depending from the plunger to engage behind the interior valve upon downward movement of the plunger preparatory to lifting the interior valve, and means to cause slight upward movement of the plunger to lift the interior valve from its seat to drain the standing valve.

In testimony whereof I affix my signature.

GEORGE WILSON GOSS.
